Primary Examiner — Charles D Hanson(57) **CLAIM**

The ornamental design for a distal femur plate, as shown and described.

DESCRIPTION

FIG. 1 is a front perspective view of a distal femur plate in accordance with the present invention showing the new design;

FIG. 2 is a top view thereof;

FIG. 3 is a right-side view thereof;

FIG. 4 is a bottom view thereof;

FIG. 5 is a left-side view thereof;

FIG. 6 is a front elevational view thereof; and,

FIG. 7 is a rear elevational view thereof.

The broken line showing of environment in the drawings is for illustrative purposes only and forms no part of the claimed design.

1 Claim, 4 Drawing Sheets(56)
